UNITED STATES PATENT OFFICE.

AUGUSTUS BISCHLER, OF BASEL, SWITZERLAND, ASSIGNOR TO THE FIRM OF BASLE CHEMICAL WORKS, OF BASEL, SWITZERLAND.

PROCESS OF MAKING INDOXYL, &c.

No. 894,579.

Specification of Letters Patent.

Patented July 28, 1908.

Application filed March 30, 1908. Serial No. 424,019.

To all whom it may concern:

Be it known that I, AUGUSTUS BISCHLER, doctor of philosophy and chemist, a subject of the Emperor of Russia, and resident of Basel, Switzerland, have invented a new and useful Process for the Manufacture of Indoxyl, its Homologues, and their Derivatives, of which the following is a full, clear, and exact specification.

10 In my United States Letters Patent No. 776884 dated December 6, 1904, a process for the manufacture of indoxyl, its homologues and their derivatives is described, which consists in adding an alkali salt of an 15 arylglycin to a heated mixture of caustic potash and metallic sodium, and, after the arylglycin has entered into reaction with part of the sodium, forming a sodium-arylamin compound, continuing to heat with an 20 addition of a primary or secondary aromatic amin. In working this process, I have found that it may be modified in that the aromatic amin may first be added to the heated mixture of caustic potash and metallic sodium, and only when the reaction with the sodium, forming the sodium-arylamin compound, has occurred, is the arylglycin salt added to the mass and the heating continued.

25 30 This new process which constitutes the present invention offers certain advantages; if powdered alkali is used for the process described in the aforesaid specification, the operation presents no difficulties whatever. 35 If, however, for the treatment of the arylglycin a liquid mixture of alkali, such as is obtained in a direct manner by dehydrating a mixture of alkalies, and metallic sodium are employed, it is not possible to add the 40 arylglycin all at once, as the development of hydrogen causes the mass to foam violently. To prevent it from foaming over it is indispensable in this case to add the arylglycin slowly in quite small portions; if the temperature during this proceeding is kept so 45 low that no indoxyl is formed, a part of the glycin becomes decomposed in consequence of the prolonged heating and the subsequent yields of indigo are less good. If, however,

50 an arylamin be allowed to react first on a melted mixture of alkali and metallic sodium, a quantity of arylglycin salt, equivalent to the sodium-arylamin compound, may afterwards be added all at once, only causing 55 an ebullition of the liberated amin, and no

foaming. The amin is again bound by the sodium present in the mixture.

The following examples illustrate the invention, the parts being by weight:

Example I. To a heated, dehydrated 60 melted mixture of 120 parts of caustic potash and 80 parts of caustic soda placed in a boiler provided with an agitator, are first added 13.8 parts of metallic sodium and when the temperature of the mass is about 220-225° C., 19 65 parts of anilin are introduced, a long reflux condenser being used; when the anilin is bound, 37.8 parts of potassium salt of phenylglycin are added through a wide tube in such a manner as to prevent any of the liberated anilin from being wasted. If some of the anilin should distil over, it must be poured back. When the anilin is again bound, the heating is continued at a temperature of 225-235° C., until the formation 75 of the indoxyl is completed. The mass is dissolved in water, the indoxyl converted into indigo by the introduction of air, the indigo is filtered, washed first with water, then with hydrochloric acid, again with 80 water, and finally with alcohol, and dried.

Example II. At a temperature of 230° C. 85 13.8 parts of metallic sodium are introduced into 180 parts of a dehydrated mixture of caustic soda and caustic potash in equimolecular proportions, and at about 220° C. 23 parts of ethylanilin are added, a large reflux condenser being used. After the amin is bound by the sodium, 37.8 parts of potassium salt of phenylglycin are added to the mass and the heating is continued at 90 230-240° C. until test portions taken from the mixture show that the quantity of indoxyl no longer increases. The indoxyl is converted into indigo, and the indigo isolated, as indicated above.

Instead of 1 molecular proportion of amin, from two to three molecular proportions may be allowed to react on the mixture of caustic potash and 3 molecular proportions of metallic sodium and the phenylglycin can be added 100 after the formation of the sodium-arylamin has occurred, but the amin which is already liberated by the introduction of the glycin and through the subsequent heating process, must be distilled off. In this case, especially when using 3 molecular proportions of amin, the formation of indoxyl must be performed at a temperature exceeding that indicated in the above examples.

What I claim is:

1. In the process for the manufacture of indoxyl, its homologues and their derivatives by heating the arylglycins and their derivatives with caustic alkali and a sodium arylamin, causing an aromatic amin of the anilin series to act first on a heated mixture of caustic alkali and metallic sodium, then adding the glycine derivative and continuing to heat until the formation of the indigo leuco-derivative is complete, as described.
2. In the process for the manufacture of indoxyl, its homologues and their derivatives by heating the arylglycins and their derivatives with caustic alkali, a sodium

arylamin and metallic sodium, causing an aromatic amin of the anilin series to act first on a heated mixture of caustic alkali and metallic sodium, then adding the glycine derivative and continuing to heat until the 20 formation of the indigo leuco-derivative is complete, as described.

In witness whereof I have hereunto signed my name this 14 day of March 1908, in the presence of two subscribing witnesses.

AUGUSTUS BISCHLER.

Witnesses:

GEO. GIFFORD,
AMAND RITTER.
